UNITED STATES PATENT OFFICE.

WILLIAM H. McALONEY, OF DENVER, COLORADO, ASSIGNOR TO THE AUTOMATIC SIGNAL LIGHT COMPANY, OF COLORADO SPRINGS, COLORADO, A CORPORATION OF COLORADO.
MEANS FOR ILLUMINATING CAR-STEPS.

961,887.

Specification of Letters Patent. Patented June 21, 1910.

Application filed August 23, 1909. Serial No. 514,272.

To all whom it may concern:

Be it known that I, WILLIAM H. McALONEY, a citizen of the United States, residing in the city and county of Denver and State of Colorado, have invented certain new and useful Improvements in Means for Illuminating Car-Steps; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to means for illuminating the steps of railways cars, being more especially intended for use on the cars of street railways, the object being to prevent accidents both in stepping off and getting on these cars.

In my improved construction, provision is made for throwing a bright light directly upon the steps of the car, a number of incandescent lamps being arranged above the opening through which the passengers enter and pass out of the car, whose rays, by the aid of a concealed reflector, are thrown directly downwardly upon the steps of the car, thus giving passengers the benefit of such illumination at all times when needed.

In equipping cars with my improved device, a reflector is placed between the two members forming the upper wall of the side of the car above the entrance. This reflector is practically concealed between the partition members of the wall of the car and is curved upwardly forming a recess in which the lamps are located, the latter being also sufficiently concealed to afford ample protection against accidental injury. At the same time, they are in position by the aid of the reflector to throw their rays upon the car steps, as well as the floor of the car in the vicinity of the steps and the ground outside thereof, thus giving perfect illumination, not only directly upon the steps but also in the vicinity thereof, both inside and outside of the car.

Having briefly outlined my improved construction, I will proceed to describe the same in detail, reference being made to the accompanying drawing, in which is illustrated an embodiment thereof.

In this drawing: Figure 1 is a vertical

section taken through the side of the car, cutting the steps below and the wall of the car above the entrance. Fig. 2 is a side elevation of the car, looking toward the entrance, the upper portion of the wall of the car being partly broken away, to disclose the lamps and the reflector co-operating therewith.

The same reference characters indicate the same parts in all the views.

Let the numeral 5 designate the floor, 6 the steps and 7 the car entrance. The wall of the car above the entrance is composed of inner and outer members 8 and 9. Between these members is located an upwardly-curved reflector 10, forming a recess 12, in which incandescent lamps 13 are located. It is evident that any desired number of these lamps may be employed, depending upon the width of the entrance. As shown in the drawing, there are three posts 14: one in the center and two on opposite sides of the entrance. Two lamps 13, are mounted upon the central post, projecting in opposite directions; while a single lamp is mounted upon each of the outer posts. This is simply a conventional arrangement but serves the purpose for an entrance of ordinary width. It is evident, however, that any other suitable arrangement or number of lamps may be employed. By reference to the drawing, it will be observed that these lamps are practically concealed from view, except in an upward direction. They are therefore peculiarly protected from injury either from the inside or outside of the car.

The reflector 10, may be composed of any suitable material.

The lamps may of course be connected with the regular illuminating circuit. No attempt therefore has been made to indicate the wiring for these lamps, since nothing is claimed upon any special circuit arrangement or connection.

Having thus described my invention, what I claim is:

1. The combination with a car whose wall above the entrance is composed of two separated members, of an upwardly-curved reflector inserted between these members and illuminating devices located in the recess between the wall members and below the reflector, substantially as described.

2. The combination with a car having a recess formed in the wall thereof above the

entrance, a reflector located in said recess and curved upwardly, in order to throw light rays downwardly upon the steps below the entrance, and an illuminating device located within the recess and below the reflector, substantially as described.

3. The combination with a car having steps and an entrance above the steps, the said car having a longitudinal recess formed in its wall above the entrance and extending

the width of said entrance, and incandescent lamps located in the said recess, for the purpose set forth.

In testimony whereof I affix my signature in presence of two witnesses.

WILLIAM H. McALONEY.
